15 Claims. (Cl. 149—16)

This invention relates to machines for operating upon hides, skins, and leather. While the invention is illustrated as embodied in a shaving machine, it will be understood that the invention and various important features thereof may have other applications and uses, as, for example, in buffing, cutting, and grinding machines.

In treadle operated shaving machines, as heretofore constructed, a fixed adjustable abutment has been provided for limiting the movement of the bed roll in a direction toward the bladed cylinder, the purpose being to limit the depth of the cut by predetermining the spacing between the bed roll and the shaving cylinder when the former is in work presenting position with respect to the latter. When it is desired to change the spacing the operator resets the adjustable abutment. It will be understood that this may be done as a practical matter in conditioning the machine for operations upon assorted lots of work which lots differ one from another substantially in thickness. It is impractical, however, to adjust the abutment for each piece of work since such an operation would involve the expenditure of too much time and effort. It is also impractical to adjust the abutment to vary the depth of the cut for different portions of the same piece of work. Although attempts have been made to facilitate such an adjustment of the bed roll in a shaving machine such devices have been used but little by the operator of the machine since to do so would slow up operations and reduce the output upon which his pay depends. Furthermore, adjustment of a fixed abutment while operating on a given piece of work was liable to result in the production of a pronounced offset at the line of demarcation between the shaved areas before and after adjustment. Hence, the operator had to exercise unusual care and skill after such adjustment or have his work condemned as unsatisfactory.

In shaving operations upon skins and other pieces of leather, it is desirable to vary the depth of the shaving cut while operating upon each piece of work, for the reason that various portions of each hide, skin or other piece of leather differ substantially not only in thicknesses but in texture. For instance, the flank and belly portions of a skin are of considerably looser texture than the portions along the backbone line and in the butt of the skin. Furthermore, in consequence of certain finishing operations the spongy parts of a skin, after shaving, become thinner than the denser portions in the middle of the skin and in the butt portions thereof.

Hence, the looser textured flank and belly portions should not be shaved as deeply as the denser butt and back portions.

It is an object of this invention to facilitate machine operations upon skins and pieces of leather in such manner that the operator may readily vary the pressure at which machine operations are performed to suit the requirements of various portions of each skin or other piece of leather undergoing treatment. It is a further object of the invention to provide an improved work support mechanism of general utility in leather manufacturing machinery, said mechanism being distinctive particularly by reason of the facility with which it may be adjusted to suit variations in certain characteristics of the work.

To these ends, and in accordance with an important feature of the invention there is provided, in a machine comprising a manually operable member to effect relative movement of a tool and a work support into position to operate on a piece of work, means under control of said manually operable member to effect relative positioning of the work support and tool selectively at various distances with respect to each other while the tool is operating on the piece of work so that the work may be operated upon in a manner to suit varying requirements in different portions thereof. Conveniently the said means comprises a yielding abutment and a fixed abutment, the latter being operative to determine one co-operative position of the work support and tool and to set a positive limit to the relative approaching movement of the work support and tool. The yielding abutment is operative to effect another positioning of the tool and work support relative to each other and is of such assistance in controlling the relative positions of the work support and tool that the operator may, with ordinary care, secure treatment of the work suited to the conditions in various portions thereof while at the same time avoiding any sudden transition in the pressure at which treatment of the work is performed, or abrupt change in the depth of the cut where the tool is an abrasive member or a cutter operative to remove portions from a surface of the work.

In the illustrated construction wherein a fixed and a yielding abutment are employed in positioning a work support with respect to a shaving tool, the fixed abutment is adjustable to suit the work support to variations in the thickness dimensions of different lots or batches of work, the yielding abutment being associated with the

fixed abutment and under the control of a treadle to secure different controlled positions of the work support within a range predetermined by the initial spacing of the abutments, a gradual 5 adjustment of the work support from one work presenting position to another, during treatment of a given piece of work, being secured through proper control of the treadle by the operator. In a preferred construction, the yielding abut- 10 ment surrounds the fixed abutment and is held by a spring in projected position beyond the fixed abutment, the two abutments being simultaneously adjustable as a unit in a supporting member carried by the machine frame wherein 15 they may be readily fixed in adjusted position, the fixed and yielding abutments being also relatively adjustable to provide for variation in the range of controlled adjustment of the work sup- 20 port to suit the characteristics of different por- tions of a given piece of work.

These and other important features of the invention and novel combinations of parts will now be described in detail in the specification and then pointed out more particularly in the ap- 25 pended claims.

Fig. 1 of the drawing is a view in side elevation, and partly in section, of a shaving machine illustrating one embodiment of the invention; and

Fig. 2 is a detail view, in section, of the work 30 support adjusting means.

In the illustrated machine, which is designed particularly for shaving operations upon hides and skins, there is provided a bladed cylinder 4 mounted for rotation in bearings carried by a 35 machine frame 6. For presenting each piece of work to the bladed cylinder 4 there is provided a work support comprising a bed roll 8 rotatably carried at the upper ends of swing arms one of which is shown at 10, as pivotally mounted 40 upon a shaft 12 carried by the machine frame 6. For moving the work support toward the bladed cylinder 4 there is provided a treadle mechanism comprising a bell crank lever 14 pivoted upon a shaft 16 carried by the machine frame, 45 the bell crank lever having a tread portion 17 and also an upright arm portion 18 provided with a set screw 20 adapted to contact with a cross- 50 bar 22 connecting the lower portions of the swing arms 10. It will be clear from an inspection of Fig. 1 that upon depression of the tread portion 16 of the treadle 14 the bed roll 8 at the upper ends of the swing arms 10 will be moved to the right in Fig. 1 to press the work against the bladed cylinder 4.

Means is provided for limiting the movement of the bed roll 8 in the direction toward the bladed cylinder 4, the said means comprising a fixed abutment 24 and a movable abutment 26 which normally projects beyond the fixed abutment 24. As shown, both abutments 24 and 26 are carried by a sleeve member 28 which is exteriorly screw threaded for adjustment in an interiorly screw threaded circular opening in a tie or girder 30 rigidly mounted upon the machine frame 6. It will be understood that this adjustment of the abutments as a unit is made to suit the machine for operations upon various lots of work which differ substantially in thickness. For holding the sleeve 28 in its adjusted position 70 with respect to the girder 30 there is provided an annular nut member 32 screw threaded upon the sleeve 28 and having a hub portion with a flat surface to contact with a surface on the girder 30, the said annular member 32 being of a size to furnish sufficient leverage so that it may

be readily manipulated by the operator to locking or unlocking position. Screw threaded within a cylindrical chambered portion of the sleeve 28 is a second sleeve member 34 which is also interiorly screw threaded to support adjustably the fixed abutment 24 which has a screw threaded portion fitting the interiorly screw threaded portion of the sleeve 34, a nut 36 being provided for holding the abutment member 24 in adjusted position. To facilitate rotation of the abutment 24 within the sleeve 34 it has a squared end 38 adapted to be engaged by a wrench or other suitable tool. This adjustment of the abutment 24 is for the purpose of determining the normal or initial distance between the operative surfaces of the two abutments 24 and 26. This distance may measure from one-third to one millimeter, depending on the thickness and quality of the skins, it being understood that said distance or spacing of the abutments may be much greater in conditioning the machine for shaving operations on heavy hides or on splits from the latter.

Upon inspection of Fig. 2 it will be observed that the yielding abutment 26 is in the form of a cap having a collar 40 which is held yieldingly against an annular shoulder at one end of the sleeve 28 by means of a spring 42 which presses against an inner surface of the cap or yielding abutment 26 and also against the adjacent end of the sleeve 34 which may be adjusted to vary the tension of the spring 42. To facilitate adjustment of the sleeve 34 the latter is provided with recesses 44 adapted to be engaged by a spanner tool the forks of which are spaced to engage in said recesses. Adjustment of the sleeve 28 after proper manipulation of the locking nut 32 may be readily accomplished by turning a wheel member 46 which is rigid with said sleeve 28.

In operating the machine a piece of work such 40 as a tanned skin is draped over the bed roll 8 with a portion interposed between the bed roll and the bladed cylinder 4, this introduction of the work taking place while the bed roll 8 is swung to the left in Fig. 1 in spaced relation to the cylinder 4. Upon depressing the tread part 16 of the treadle 14 the bed roll 8 is caused to move toward the bladed cylinder 4 until the lower end 22 of the swing arms 10 engages the yielding abutment 26, it being assumed that thicker and looser textured portions of the work (such as a hide) are being presented to the bladed cylinder 4 for treatment. While abutment 26 is yieldable, the spring 42 is of sufficient strength to maintain said abutment in operative position in the initial depression of the treadle 14. At least, that is what happens when the operator gets the "feel" of his machine. As the shaving operations are continued the work is constantly shifted to present untreated portions to the cylinder 4. As the thinner denser portions of the work are approached the operator presses a little heavier on the tread 45 50 55 60 65 70 75 80 85 90 95 100 105 110 115 120 125 130 135 140 145 150 155 160 165 9735 9740 9745 9750 9755 9760 9765 9770 9775 9780 9785 9790 9795 9800 9805 9810 9815 9820

of the yielding abutment 26 makes it possible gradually to vary the depth of the cut made by the cylinder 4, thus eliminating any abrupt offset such as would be produced if the yielding abutment 26 were suddenly forced back into alignment with the fixed abutment 24. In shaving operations upon skins, the denser, thicker back and butt portions are presented to the machine first and the yielding abutment 26 employed in 10 positioning the bed roll 8. Subsequently to operate on the thinner flank and belly portions, the treadle 16 is further depressed to remove portions from the flesh surface of said flank and belly portions. It will be clear, therefore, that through 15 provision of the fixed and yielding abutments various portions of each piece of work may be treated in a manner to secure the best results, the work being at all times under the control of the operator whose work is facilitated by proper 20 positioning of the work support by the fixed and adjustable abutments.

Having described my invention, what I claim as new and desire to secure by Letters Patent of the United States is:

25 1. In a machine for operating upon hides, skins, and leather, a tool and a work support relatively movable away from each other to receive a piece of work and subsequently toward each other into position to operate on the work, 30 a manually operable member to cause the relative approaching movement of the tool and work support, and means to effect relative positioning of the work support and tool selectively, under the control of said manually operable member, at 35 various distances from each other during operations on a piece of work.

2. In a machine for operating upon hides, skins, and leather, a tool and a work support relatively movable into position to operate upon 40 a piece of work, a manually operable member to cause such relative movement, and a stop device carried by the machine frame and arranged to effect relative positioning of the work support and tool selectively, under control of said 45 manually operable member, at different distances with respect to each other while the tool is operating on a piece of work.

3. In a machine for operating upon hides, skins, and leather, a tool and a work support 50 relatively movable into position to operate upon a piece of work, a manually operable member to cause such relative movement, and means comprising a fixed and a movable abutment to effect relative positioning of the work support and tool, 55 under control of said manually operable member, alternatively in different spaced relations with respect to each other while the tool is operating on a piece of work.

4. In a machine for operating upon hides, 60 skins, and leather, a tool, a work support movable to present a piece of work to the tool, a member manually operable to move the work support to work presenting position with respect to said tool, and a stop device comprising relatively movable parts operative to engage and hold the work support at different distances from said tool while the latter is operating upon a piece of work.

5. In a machine for operating upon hides, 70 skins, and leather, a rotary tool and a work support relatively movable to operate upon pieces of work, a treadle to cause such relative movement of the work support and tool, and a stop device comprising a fixed and a movable abutment to effect relative positioning of the work support and tool at different distances with respect to each

other while the tool is operating upon a piece of work.

6. In a machine for operating upon hides, skins, and leather, a bladed cylinder, a work support comprising a bed roll to present pieces of work to the bladed cylinder, a treadle to move the bed roll to work presenting position with respect to said cylinder, and a yielding abutment to engage the work support to hold the bed roll selectively at different distances with respect to 10 said bladed cylinder while the latter is operating on a piece of work.

7. In a machine for operating upon hides, skins, and leather, a bladed cylinder, a work support comprising a bed roll to present pieces 15 of work to the bladed cylinder, a treadle to move the bed roll to work presenting position with respect to said cylinder, and a fixed and a yieldable abutment having their operative surfaces spaced a predetermined distance from each other 20 and operative to hold the work support during treatment of the work selectively at various distances with respect to the cylinder within the range provided by the spacing of the operative surfaces of the abutments.

8. In a machine for operating upon hides, skins, and leather, a bladed cylinder, a work support comprising a bed roll to present pieces of work to the bladed cylinder, a treadle to move the bed roll to work presenting position with 30 respect to said cylinder, and a fixed and a yieldable abutment having their operative surfaces spaced a predetermined distance from each other and operative to hold the work support during treatment of the work selectively at various distances with respect to the cylinder within the range provided by the spacing of the operative surfaces of the abutments, said abutments being mounted for adjustment relative to each other 35 to vary the spacing of their operative surfaces.

9. In a machine for operating upon hides, skins, and leather, a bladed cylinder, a work support comprising a bed roll to present pieces of work to the bladed cylinder, a treadle to move the bed roll to work presenting position with respect to 45 said cylinder, an abutment yieldingly mounted and operative to position the bed roll with respect to said bladed cylinder during treatment of the work, and a fixed abutment arranged to become operative upon completion of the retractive 50 movement of the yieldable abutment to locate the bed roll at a lesser distance from the bladed member than that initially provided by the yielding abutment.

10. In a machine for operating upon hides, 55 skins, and leather, a work support movable to present a piece of work to a tool, a treadle member to operate the work support, and means comprising a stop device against which the work support is pressed by the treadle to locate the work support at different distances with respect to the tool while the latter is operating on a piece of work.

11. In a machine for operating upon hides, 60 skins, and leather, a work support movable to present a piece of work to a tool, a manually operable 65 member to operate the work support, and means comprising a fixed and a movable abutment arranged to engage the work support to locate the latter alternatively in one or the other of two spaced positions with respect to said tool while 70 the latter is operating on a piece of work.

12. A stop device for use in leather working machines to position a moving member selectively at various distances from a stationary member during operations on a piece of work which com- 75

prises a sleeve adapted to be adjustably mounted in a stationary part of the machine frame, an abutment rigidly carried by said sleeve to position the moving member in a predetermined working relation to the stationary member, and another abutment yieldingly mounted relatively to said sleeve and arranged to project beyond the stationary abutment to position the moving member initially in another predetermined working relation to the stationary member.

10. 13. A stop device for use in leather working machines to position a moving member selectively at various distances from a stationary member during operations on a piece of work which comprises a sleeve adapted to be adjustably mounted in a stationary part of the machine frame, an abutment rigidly carried by said sleeve to position the moving member in a predetermined working relation to the stationary member, and an abutment mounted upon and yieldable relatively to said sleeve and arranged to project beyond the stationary abutment to position the moving member initially in another predetermined working relation to the stationary member, said abutments being relatively adjustable to vary the distance between the operative faces of said abutments thereby to change the range of adjustment of the

15. 14. A stop device for use in leather working machines which comprises a sleeve adapted to be adjustably mounted in a stationary part of the machine frame, an abutment rigidly carried by said sleeve, and an abutment yieldingly mounted in said sleeve and arranged to project beyond the stationary abutment, said rigidly carried abutment being mounted for adjustment within said sleeve.

20. 15. A stop device for use in leather working machines which comprises a sleeve adapted to be adjustably mounted in a stationary part of the machine frame, a second sleeve member rotatably mounted within the first-mentioned sleeve member, an abutment fixedly but adjustably connected to said second sleeve, an abutment slidably mounted within the first-mentioned sleeve and having a portion projecting therefrom, and a spring arranged between the second-mentioned sleeve and the movable abutment to hold the latter yieldingly in projected position with its operative face in spaced relation to the operative face of the fixed abutment.

PAUL NIJESSEN.
